PLUGGING AND ACCELERATING CONTROL

Henry D. James, Edgewood, Pa., assignor to Westinghouse Electric & Manufacturing Company, East Pittsburgh, Pa., a corporation of Pennsylvania

Application August 20, 1932, Serial No. 629,645

7 Claims. (Cl. 172—179)

This invention relates to control systems for electric motors which systems utilize electronic discharge devices to control the operation of the motors.

5 One object of this invention is to provide for controlling the reversing and acceleration of a motor by electronic discharge devices.

Another object of this invention is to provide an electronic discharge device responsive to selected changes in the operating characteristics 10 of an electric motor to control the starting and reversing of the motor.

A still further object of this invention is to control the discharge of a cold-cathode discharge 15 tube in response to variations in characteristics of the armature current of a motor to control the acceleration and reversal of the motor.

Other objects and advantages will become more apparent from a study of the following specification, when considered in conjunction with the accompanying drawings, in which:

Figure 1 designates a system of control particularly useful as a plugging control system controlling the operation of a reciprocating motor; 25 and

Fig. 2 represents a system of control for accelerating a direct current motor in a substantially predetermined interval of time by the use of a cold-cathode tube.

30 Referring more particularly to Fig. 1, reference character 1 represents a direct current motor, the operations of which are to be controlled, whereas reference characters 2 and 3 designate the buses for supplying the direct current energy to the 35 motor 1. The motor is provided with a plurality of reversing switches 4 and 5, and 6 and 7, respectively. To prevent damage to the motor during starting, the accelerating resistor 8 is provided. This resistor has one section 9 thereof, 40 designated the plugging resistor, of a relatively high resistance value.

A cold-cathode tube 10 is provided for controlling the shunting operation of the plugging contactor 11 in such manner that this contactor 45 is never closed during the plugging operation before the motor has substantially come to rest after having operated in a given direction.

One of the chief advantages of a cold-cathode tube is that the starting operation or the reversing 50 operation, as the case may be, is not impaired by the delay caused by the belated operation of electromagnetic devices or the time delay of a thermionic device requiring the heating of a filament. A cold-cathode tube properly adjusted 55 breaks down at exactly the time desired and thus

does not function after an undetermined relatively long time constant as do hot-cathode devices.

To accomplish this novel and advantageous feature, the cold-cathode tube 10 is provided with a resistor 12 which resistor is interconnected with the accelerating resistor sections 13 and 14 of the armature resistor 8 by the conductors 15 and 16. The grid 17 of the cold-cathode tube 10 is so positioned with reference to the connecting points 18 and 19 of the conductors 15 and 16, respectively, that a variation of current in the conductors 15 and 16 of a predetermined amount will cause the cathode tube 10 to be deenergized, i. e., cease its discharging operation from the plate 20 to the cathode 21.

A more complete understanding of the novel features of this invention can best be had from a study of the sequence of operation of the elements constituting the plugging controller.

Assuming that conductors or buses 2 and 3 are 75 suitably energized and it is desired to start the operation of the motor 1 to operate the machine connected thereto, which, for this particular application, usually constitutes a reciprocating device. To start the operation, the attendant operator 80 operates the push button starting switch 22 thereby establishing a circuit from the conductor 2 through stop switch 23, starting switch 22, and actuating coil 24 of the line contactor 25 to the energized conductor 3. The operation of the line 85 contactor 25 closes the upper auxiliary contact members 26 to establish a holding circuit for the actuating coil 24, and causes a closing of the lower auxiliary contact members 27 to effect the energization of the control relay 28. The circuit 90 for the control relay may be traced from the battery 29 through the lower auxiliary contact members 27 of contactor 25, actuating coil 30 of the control relay 28, resistor 12, and resistor 31, back to the battery.

95 It will be noted that the plate 20 of the tube 10 is connected to the positive terminal of the battery and that the grid 17 is connected at point 32, which may be varied, to the resistor 12. A potential of a given value is therefore impressed across 100 the gap between the plate 20 and the grid 17, and the tube breaks down causing a current to flow through the tube and through the resistor 31. This increased current immediately causes the 105 operation of the control relay 28 to close its contact members.

In the arrangement shown, the coil 30 is sufficiently energized to actuate the control relay 28 by reason of the repeated discharges of the condenser 33. The condenser 33 coacts with the dis- 110

charge in the tube, causing an oscillatory current to flow in the network including the tube 10 and the condenser 33, and, hence, producing a variation in polarity of the potentials impressed upon the electrodes of the tube. By reason of the variation in polarity of the potentials, the discharge in the tube is interrupted when the grid 17 is reverted to its original electrical condition, after having been given a potential favorable to discharge between the electrodes 20 and 21 of the tube 10. The normal variation of the voltage across resistor sections 13 and 14 during starting does not affect the bias of the grid sufficiently to stop the rapidly repeating discharges of the tube 10. These rapid discharges thus cause sufficient current to flow in coil 30 to operate the control relay.

The closing of the contact members of the control relay 28 does not effect the operation of any of the contactors 11, 34, or 35 unless the controller 36 has first been actuated to effect an operation of the motor 1 in the desired direction.

When the controller segments 37 and 38 are moved towards the left, the forward direction, circuits are established for the actuating coils of the directional contactors 4 and 5. These circuits may be traced from the energized conductor 2 through actuating coil 39 of directional contactor 4 to controller segment 37 and from energized conductor 2 through actuating coil 40 of directional contactor 5 to the controller segment 37 from whence the circuits are completed through conductor 41 to the negatively energized conductor 3.

The operation of the controller as first specified also establishes a circuit from the energized conductor 2 through conductor 42, actuating coil 43 of the plugging contactor 11, the contact members of the control relay 28 and conductor 44 to the negatively energized controller segment 37.

Since the plugging resistor 9 is of a relatively high resistance value and is not, as such, a part of the accelerating resistor for the motor, it is not particularly important whether the plugging contactor 11 closes immediately after the operation of the controller or not. The important operation of the plugging contactor 11 is to limit the armature current during the plugging operation in a manner to be pointed out more in detail hereinafter.

The line contactor being closed, as heretofore explained, a circuit is established from the conductor 2 through directional contactor 4, the armature 45 of the motor 1, directional contactor 5, conductor 46, series field winding 47 of the motor 1, accelerating resistor sections 13 and 14 and the plugging resistor section 9 and contact members of line contactor 25 to the negatively energized conductor 3. During the normal acceleration of the motor, the plugging contactor 11 will, of course, operate immediately so that the resistor 9 remains in the armature circuit but a very short interval of time. However, the operation of the plugging contactor causes the closing of the auxiliary contact members 51 of the plugging contactor 11 thereby establishing a circuit for the first accelerating contactor 34. This circuit may be traced from the energized conductor 2 through conductor 49, actuating coil 50 of the accelerating contactor 34 and auxiliary contact member 51 of the plugging contactor 11 to the negatively energized conductor 3.

The accelerating contactors 34 and 35 are provided with suitable time limit devices 53 and 52, respectively, which prevent the closing of these

contact members after being energized for a predetermined interval of time. The closing of contact members 51 therefore does not effect the immediate closing of the accelerating contactor 34, but the contactor closes only after the lapse of a definite interval of time determined by the adjustment of the time limit device 53. However, when accelerating contactor 34 closes, the resistor section 14 is shunted and auxiliary contact members 54 of the accelerating contactor 34 are closed thereby establishing a circuit from conductor 49 through actuating coil 55 of accelerating contactor 35, auxiliary contact members 54, and conductor 56 to the negatively energized conductor 3. It will thus be noted that the motor is brought up to full operating speed within a substantially fixed short interval of time.

Assuming that the attendant operates the controller 36 in the reverse direction, i. e., plugs the motor to close the directional contactors 6 and 7. A mere inspection will show that this operation connects actuating coils 57 and 58 of directional contactors 6 and 7, respectively, to the conductor 2 and by means of controller segment 38 and conductor 41 to the negatively energized conductor 3. Closing of the directional contactors 6 and 7 connects the armature 45 of the motor to the conductors 2 and 3 in such a manner that the counter-electromotive force of the armature 45 is additive to the applied voltage. It is, therefore, obvious that substantially twice the applied voltage will be impressed across resistor sections 13 and 14, thereby counteracting the effect of the battery 29 between the points 18 and 19 with the result that the cold-cathode tube is extinguished because the voltage across the tube is very materially reduced.

Coil 30 is thus deenergized because resistor 12 has a resistance value sufficiently high to prevent sufficient current to flow in coil 30 to actuate the control relay 28. Regardless of the fact that the controller is in the reverse position, coil 43 is deenergized and the plugging contactor 11 remains open. Since the contactors 34 and 35 are interlocked with the plugging contactor, resistor sections 13 and 14 also remain in the circuit of the armature 45.

As the motor decelerates the counter-electromotive force decreases and when the resistance drop across resistor sections 13 and 14 is substantially zero, i. e. the motor armature ceases rotating, the bias on the grid 19 will again be favorable to discharge of the tube 10. Flashes thus occur in rapid succession through the tube causing sufficient current to flow through coil 30 to operate the control relay 28 which then in turn effects the operation of the plugging contactor 11. From the foregoing explanation it is obvious that the plugging resistor 9 remains in the circuit until the plugging operation is completed and thereafter the acceleration of the motor takes place in the reverse direction in a predetermined manner.

Referring to the modification shown in Fig. 2, wherein a cold-cathode tube 88 is utilized to control the acceleration of the motor 60. In this modification the rise and fall of the armature current after the closing of the line contactor and the closing of successive accelerating contactors is taken advantage of to accelerate a direct current motor in a predetermined manner.

It will be noted that the principal electrodes 85 and 87 of a cold-cathode tube 88 are connected in parallel with a condenser 84, and a resistor 80 and secondary 81 of a transformer 100 connected in series. The control electrode or grid 150

86 of the tube 88 is connected at any selected position on the resistor 80 to vary the adjustment of the tube 88. This assembly of circuits may be energized from a source of direct current such as 5 a battery 89 through conductor 82 and resistor 83.

The voltage of the battery 89 and the other constants of the circuits associated with the tube 88 are so chosen that the tube will not break down when only the positive bias provided by 10 the battery is available. To more clearly appreciate the novel and useful features of the modification shown in Fig. 2, a sequence of operation will be given.

Assuming conductors 61 and 66 are energized 15 and the attendant actuates the starting push button switch 63 to energize the line contactor 65 through stop switch 62, the auxiliary contact member 73 of line contactor 65 close and the line contactor 65 closes and a holding circuit for coil 20 64 is established through auxiliary contact members 65'. Closing of the line contactor establishes the field circuit for the motor 60 from conductor 61 through rheostat 101, field winding 102, conductor 67, and auxiliary contact members 25 of line contactor 65 to the negatively energized conductor 66. An armature circuit is also established from conductor or bus 61 through the armature 103 of the motor 60, primary winding 80' of transformer 100, resistor sections 69, 70 30 and 71 of accelerating resistor 68 and auxiliary contact members of line contactor 65 to the negatively energized conductor 66.

Since contact members 73 are closed a certain positive bias will be placed on grid 86 but not 35 sufficient to cause a break down of tube 88. The rise of armature current immediately after the closing of the line contactor establishes a variable voltage at the primary 80' and secondary 81 of the respective transformer terminals of a 40 polarity such as indicated by the full line arrows. As soon as the current change in the rising direction has attained a pre-selected value the tube 88 breaks down and thereafter passes current by rapidly recurring impulses, the condenser 84 discharging at each impulse.

The motor soon accelerates and the rise in counter-electromotive force soon causes a decay of armature current with the result that the polarities of the voltages at the respective 50 transformer terminals will be such as shown by the broken line arrows shown in Fig. 2. The bias on the grid will thus become less positive and the successive discharges of the condenser 84 through tube 88 will cease.

55 During the time the tube is rapidly breaking down a considerable current passes through coils 74, 76 and 78, thereby holding the accelerating contactors 75, 77 and 79 open. However, as soon as the tube 88 ceases to pass current, coil 74 is 60 not strong enough to prevent coil 90, which is subject to full line voltage, from closing accelerating contactor 75. As soon as resistor 71 is shunted by the accelerating contactor 75 the armature current again rises causing the tube 88 to again break down. Coils 74, 76 and 78 are 65 thus again energized and coil 76 prevents coil 91, though this coil 91 be energized by full line voltage through conductor 93 and auxiliary contact members of accelerating contactor 75, from 70 closing the accelerating contactor 77. As soon as the armature current has gone through its rise and fall the tube 88 is again extinguished and the accelerating contactor 77 closes shunting the resistor section 70.

75 The coils 78 and 92 of accelerating contactor

79 are similarly energized and eventually resistor 89 is shunted. The one tube 88 may thus be utilized for any number of accelerating resistors and the motor may thus be accelerated within a substantially predetermined interval of time.

80 Applicant is of course aware that any one skilled in the art, after having the benefit of the teachings of this invention, can readily devise other circuit arrangements than the particular arrangements herein shown. He, therefore, wishes to be limited only by the appended claims and the pertinent prior art.

85 I claim as my invention:

1. In a system of control for controlling the acceleration of a motor by the successive actuation of the accelerating contactors, in combination, accelerating contactors, control means for the accelerating contactors including, a battery, a cold-cathode discharge device having principal electrodes and a control electrode, a switch for connecting the principal electrodes to the battery, circuit connections for subjecting the control electrode to a voltage having a definite relation to an operating characteristic of the motor to be controlled and a capacitor interconnected 90 with the discharge device and adapted to control the discharge device.

95 2. In a system of control for electric motors, in combination, a motor, a current limiting resistor, having a plurality of sections, for the motor, means for shunting given sections of said resistor, a line contactor, a battery, a cold-cathode discharge tube having main electrodes and a control electrode, means responsive to the operation of the line contactor for connecting the 100 main electrodes to the battery, a condenser and a resistor and transformer secondary connected in series connected in parallel with the main electrodes, circuit connections for connecting the control electrode at any selected point on said last 105 named resistor, a primary of a transformer responsive to electrical characteristics of the motor whereby said tube is caused to start its discharge in response to certain of said electrical 110 characteristics and to stop its discharge at certain other electrical characteristics, and means controlled by said tube to effect the operation of said resistor shunting means in a predetermined sequence.

115 3. A control system for electric motors comprising, a motor, a cold-cathode tube, means for effecting the starting of the discharge of the tube in response to certain changes in the armature current of the motor, means responsive to certain other changes of the armature current to stop the discharge of the tube, and means responsive to the operations of said tube to control the starting sequence of the motor.

120 4. A control system for a reversing motor comprising, a motor, a line contactor, reversing switches, a reversing controller, an accelerating resistor having a plurality of sections, a plugging resistor, a cold-cathode tube having a pair of main electrodes and a control electrode, a condenser, a control resistor, a battery, means operable by the line contactor for connecting said main electrodes, control resistor, and condenser in parallel circuit relation to said battery, circuit connections including a selected portion of said 135 control resistor connected in parallel to selected sections of said accelerating resistor, circuit connections interconnecting said control electrode to any selected point on the control resistor intermediate the selected portion of the control re- 140 145 150

5. In a system of control for electric motors, in combination, a motor, a current limiting resistor for the motor, means for shunting the resistor for the motor, a line contactor, a battery, a cold-cathode discharge device having main electrodes and a control electrode, means responsive to the operation of the line contactor for connecting the main electrodes to the battery, a condenser, and a resistor and transformer secondary connected in series, connected in parallel with the main electrodes, circuit connections for connecting the control electrode at a selected point on said last named resistor, a transformer primary winding responsive to electrical characteristics of the motor whereby said tube is caused to start its discharge in response to certain of said electrical characteristics and to stop its discharge at certain other electrical characteristics, and means controlled by said discharge device to control the operation of said resistor shunting means.
6. A control system for a reversing motor comprising, a motor, a line contactor, reversing switches, a reversing controller, a series resistor connected in series with the motor, a plugging resistor, a cold-cathode tube having a pair of main electrodes and a control electrode, a con-
5. In a system of control for electric motors, in combination, a motor, a current limiting resistor for the motor, means for shunting the resistor for the motor, a line contactor, a battery, a cold-cathode discharge device having main electrodes and a control electrode, means responsive to the operation of the line contactor for connecting the main electrodes to the battery, a condenser, and a resistor and transformer secondary connected in series, connected in parallel with the main electrodes, circuit connections for connecting the control electrode at a selected point on said last named resistor, a transformer primary winding responsive to electrical characteristics of the motor whereby said tube is caused to start its discharge in response to certain of said electrical characteristics and to stop its discharge at certain other electrical characteristics, and means controlled by said discharge device to control the operation of said resistor shunting means.
7. A motor control system, comprising in combination, a main source of direct current power, a motor, a line contactor for connecting the motor to said main source of direct current power, an auxiliary source of direct current power, an electronic discharge device having a pair of principal electrodes and a control electrode, means for connecting the principal electrodes to said auxiliary source of power, said control electrode being disposed to have its voltage bias controlled by an operating characteristic of the motor, means for rapidly effecting successive discharges of the discharge device after the closing of the line contactor, means for intermittently interrupting said successive rapid discharges through variations of said motor operating characteristics, and means responsive to said intermittent operations to effect the acceleration of the motor in a predetermined manner.
